UNITED STATES PATENT OFFICE.

MALCOLM J. GRAHAM, OF BEAUMONT, TEXAS.

MONOLITHIC WALL.

1,405,579.

Specification of Letters Patent. Patented Feb. 7, 1922.

Application filed May 8, 1920. Serial No. 379,813.

To all whom it may concern:

Be it known that I, MALCOLM J. GRAHAM, a citizen of the United States, and a resident of Beaumont, in the county of Jefferson and State of Texas, have invented certain new and useful Improvements in Monolithic Walls, of which the following is a specification.

My present invention relates generally to concrete wall construction and more particularly to a monolithic wall, my object being the provision of a wall construction of simple inexpensive construction in connection with which both the inside and outside surfaces may be similarly formed and ornamented as desired, as well as one which will be strong and durable and is capable of easy quick formation.

With these general objects in mind my invention proposes a wall construction such as shown in the accompanying drawing, which illustrates my invention and forms a part of this specification and in which,

Figure 1 is a side view, partly broken away and in section,

Figure 2 is a horizontal section therethrough,

Figure 3 is a detail horizontal section on an enlarged scale, and

Figures 4 and 5 are detail perspective views of portions of two forms of furring strips, the former Figure 4 being shown in Figures 1, 2 and 3.

Referring now to these figures my invention proposes the formation of a concrete wall by the application of concrete 10 upon opposite sides of and between a series of vertically disposed frames 11 disposed in aligned and laterally spaced relation upon any suitable base which may for instance be a previously poured or otherwise formed foundation a part of which is indicated at 12 in Figure 1.

Each of the frames 11 includes vertical parallel side members 13 preferably formed of wooden beams, with cross beams 14 rigidly spacing the same apart, a series of vertical rods or wires 15 being utilized at the sides, and connected to the cross beams 14, to form supports for the opposite walls of the frames, the latter of which are preferably in the nature of tar or other waterproof paper 16 secured along the edges of the side beams 13 by means of furring strips 17.

The furring strips above mentioned are

preferably in the nature of metal strips and are placed not only for the purpose of securing the paper walls 16 upon the frames 11 but are also utilized as a means of spacing continuous mesh or other foraminous or reticulate metal reinforcements 18 along the inner and outer faces of the frames and for connecting these reinforcements in place.

As seen in Figure 4 the furring strips 17 may be in the form of flanged ribs, the flanges of which are secured to the frame sides and the ribs of which have openings 19 to which the continuous mesh reinforcements 18 may be laced or tied by lacing or tie wires 20 as seen particularly in Figure 3. On the other hand the furring strips may be in the corrugated form shown at 21 in Figure 5, the apertures 22 of which serve to receive the mesh connecting wires such as 20.

It is obvious that by virtue of the furring strips the mesh reinforcements 18 are so spaced from the opposite faces of the frames that the concrete is permitted to thoroughly bond and embed the mesh reinforcements and that, extending as it does between the several frames, the concrete forms continuous vertical studding as at 23 in Figure 2, these portions being additional reinforced by vertical reinforcing rods 24 located between the several frames and secured by ties 25 as in Figure 1 to the mesh reinforcements 18. These reinforcing rods 24 are of course embedded in the concrete 10, which latter is applied after the frames 11 have been formed and set in position and after the mesh reinforcements 18 have been applied and connected to the furring strips 17 and to the vertical reinforcing rods 24, and the placing of concrete may be accomplished in any suitable manner as for instance by the well known gunite machine, using compressed air, or other machines using mechanical force to spray the concrete in place. The concrete may thus be placed on both the outside and inside surfaces of the wall in desired thickness and closed air spaces will be formed in the wall by the several frames 11, with continuous vertical studding between the frames. When the required thickness is built up, the wall surfaces may be given any of the known concrete finishes and it is obvious that while the concrete is forced into the wall the paper covered faces of the frames are prevented from collapsing inwardly by the supporting rods or wires 15.

100
105
110

In this way it is obvious I provide a wall construction which will be light in weight and simple and inexpensive in construction by virtue of the elimination of expensive forms and the fact that the frames 11 may be previously constructed and readily set up in the wall in such manner as to allow for windows and other common wall features, and in such manner as to permit of ready application and attachment of the continuous mesh reinforcements and the vertical rod or bar reinforcements 24 of the vertical studdings.

I claim:

15 1. A monolithic wall including laterally spaced and covered frames forming air spaces therein and constituting permanent parts of the wall, continuous reticulate reinforcements secured continuously along and spaced from opposite sides of the frames; 20 vertically extending reinforcing members outwardly beyond and secured to the reticu-

late reinforcements opposite the spaces between the frames and plastic material between and around the frames and enclosing 25 said reinforcements.

2. A monolithic wall including laterally spaced and covered frames forming air spaces therein and constituting permanent parts of the wall, continuous reticulate reinforcements secured continuously along and spaced from opposite sides of the frames, vertically extending reinforcing members outwardly beyond and secured to the reticulate reinforcements opposite the spaces between the frames, each of said frames including rigidly spaced side members and water-proof covers for its opposite faces, and furring strips securing the covers to the side members of the frame and to which the 40 reticulate reinforcements are connected and plastic material between and around the frames and enclosing said reinforcements.

MALCOLM J. GRAHAM.
